FURNITURE CONSTRUCTION.

1,165,345.

Specification of Letters Patent. Patented Dec. 21, 1915.

Application filed January 7, 1915. Serial No. 947.

To all whom it may concern:

Be it known that I, Otto Rudd, a citizen of the United States, residing in the city of Kenosha, county of Kenosha, and State of 5 Wisconsin, have invented certain new and useful Improvements in Furniture Constructions, of which the following is a specification.

This invention relates to improvements in 10 furniture construction, and refers more particularly to a novel and simple arrangement for uniting cross rods and uprights to the head end or foot end of a bed frame.

The salient object of the invention is to 15 provide improved means of fastening the uprights and cross rods of the bed frame to the bed posts and top rail without perforating the tubing of which the posts and top rail is constructed, and without the necessity 20 of using extraneous fastening devices such as screws, bolts and the like.

The main idea of the invention consists 25 in confining the ends of the connecting bars, such as the filler bars or cross rods, in ferrules or caps, which are secured to the imperforate portions of the frame members, such as the post and top rail, by a connection located wholly within the area of the contacting surfaces of the end of the ferrule 30 and the frame member. Preferably the union or connection is secured by an electric welding process such, for example, as the well-known "spot" welding.

This construction and the novel arrangement 35 for assembling the units of the bed end permits of the use of extremely light metallic stock while at the same time obtaining a structure which is sufficiently strong and rigid to withstand the strains to which a structure of this kind is subjected. The use 40 of this very light metal not only materially reduces the original cost of construction but it also decreases the freight rates as by the present invention the head and foot ends of 45 the bed will weigh materially less than in prior construction of brass and iron beds. Furthermore, the bed, being much lighter than constructions of this kind which have been heretofore made, can be more readily 50 moved around by the user.

One of the difficulties experienced by the

manufacturer in brass and iron beds of this type, is in so forming the joints at the ends of the filler rods and cross bars as to avoid cracking of the enamel or paint with which 55 the bed is coated. This cracking is due to the fact that difficulty has been experienced in getting a joint which will not loosen or which will prevent any play of the parts. These objections are overcome in the present 60 invention for the reason that the ferrules, which are the parts directly connected to the uprights and top rail of the bed ends, are secured to and become substantially a unitary part of the members to which they 65 are united.

In constructing the bed units, the relatively large tubular members which form the main uprights and top rails of the end members of the bed, may first be bent to the 70 desired shape, and the ferrules or caps which are to hold the filler rods and cross bars electrically "spot-welded" in place. The cross rod or rods and the upright filler bars may then be inserted in the caps or ferrules 75 and pressed or driven into position, and the end member is then completely assembled as a unit.

It is to be understood that as far as the 80 broader aspects of the present device is concerned, the particular cross section outlined of the tubular member is immaterial.

In its broader aspects my invention is not limited to the details of construction shown except as set forth in the appended claims. 85

In the drawings Figure 1 is a front elevation of a bed unit embodying my invention. Fig. 2 is a diagrammatic view illustrating the method of securing the ferrules to the tubing. Fig. 3 is a fragmentary vertical cross section through one of the joints. Fig. 4 is a fragmentary top plan view showing the "spot-weldings" on one of the ferrules. 90

Referring to the drawings, 1 designates as 95 a whole the foot or head end of a bed. This bed unit comprises vertically extending posts or pillars 2 and 3, provided at their lower ends with casters 4 and 5 and connected at their upper ends by the horizontal top rail 100 6. This top rail is preferably formed integrally with the pillars 2 and 3, and is bent

to the shape shown before the ferrules hereinafter described are attached. It is to be particularly noted that the top rail and pillars or posts are formed from a single tubing of light weight metal. In the embodiment shown in the drawings the tubing is circular in cross section. A cross bar or lower rail 7 extends between the pillars 2 and 3 and is secured thereto at its opposite ends in the manner hereinafter described. Between the cross bar or lower rail 7 and the top rail 6 are positioned a plurality of filler bars or rods 8. The upper ends of these rods are fixed within caps or ferrules 9 secured to the top rail, and the lower ends rest in similar caps or ferrules 10 secured to the cross bar. The ends of the lower cross rail 7 are also fixed in ferrules 12 and 13 carried respectively by the posts 2 and 3. Describing now the manner of securing these various ferrules in place, which forms one of the important features of my invention, the caps are all secured to the pillars and the top rail by a connection located wholly within the area of the contacting surfaces of the ends of the ferrules and the frame members, preferably in the manner now to be described. After the main tubing has been bent to form the posts and top rail, the ferrules 9 are spot-welded to the lower face of the top rail 6 and the ferrules 12 and 13 to the inside of the posts 2 and 3. The particular mechanism by which this spot-welding is done forms no part of the present invention, but for purposes of clearness reference may be had to the diagrammatic showing of Fig. 2. The ferrule 10, the closed end of which is shaped to fit the periphery of the tubular member, is positioned as shown in Fig. 2, and the parts to be so welded placed in a suitable spot-welding machine between the electrodes. The electrodes are moved into direct contact on the ferrules 10 and lower face of the tubular member 7 (in the present instance), and then current is supplied from a suitable source, as a battery 15, by closing the switch 17. This operation spot-welds the ferrule to the tube so that it in effect becomes an integral part of the latter. Preferably the electrodes are two-point electrodes, so as to form two spot-welds 18 as shown in Fig. 4. Whether the electrodes have one point or a plurality of points is immaterial, as far as the broader aspects of the invention are concerned.

I have found that in spot-welding the parts in question it is not necessary that the electrodes both come into immediate physical contact with the parts which are directly welded. It will be noticed in the diagram that the electrode 16 comes into contact with the tubular member 7 at the lower face of the latter. The spot-welding is performed in this manner as efficiently as

if an arbor were inserted in the tubular member 7. No difficulty would of course be experienced in putting an arbor in the straight tube 7, but if the upper ferrule 9 were not welded to the top rail 6 until after the outer frame was bent into position, then it can be readily seen that difficulty would be experienced in inserting an arbor in the top rail 6. It is to be understood of course that the ferrules 9 are secured to the top rail, and the ferrules 12 to the pillars in the same manner as the ferrules 10 are secured to the bottom rail 7. After the ferrules have all been secured in place the filler bars 8 have their ends inserted in the respective ferrules 9 and 10, and are pressed, driven or otherwise forced into position. The ends of the bottom rail 7 are also similarly inserted in the ferrules 12 and 13, the pillars being sprung sufficiently to permit of the insertion of the ends of the rail 7 in its ferrules. By this simple operation the bed unit is now completely assembled.

It is to be noted that the entire bed unit is constructed without perforating any portion of the tubing and without the use of rods or other members extending into the tubes, and there is also a total absence of any extraneous fastening devices. The permanent union between the ferrules and the outer frame of the bed unit prevents the parts working loose at these joints and thus obviating the difficulty heretofore referred to. It is of course apparent that various other forms and shapes of tubing can be employed, and I do not desire to limit the invention except as specified in the appended claims.

I claim as my invention:

1. In a furniture construction, the combination with spaced hollow metallic frame-members, and a connecting member extending therebetween, of means for holding said connecting member rigid to the frame-members, comprising opposed ferrules having open ends fitting over the ends of the connecting member and closed ends abutting against the frame-members and directly secured thereto while maintaining the latter imperforate. 105

2. In a furniture construction, the combination with a hollow metallic frame-member and a bar extending in angular relation thereto, of means for holding said bar rigid to the frame-member, comprising a ferrule having one end telescopically engaged with 115 said bar and its opposite end abutting against and united to the outer surface of the frame-member, the area of union being positioned wholly within the area of contacting surfaces of the ferrule and frame-member while maintaining imperforate the portion of the frame-member to which the ferrule is secured. 120 125

3. In a furniture construction, the combination with spaced hollow metallic frame-members and a connecting member extending therebetween, of means for holding said
5 connecting member rigid to the frame members comprising opposed ferrules having open ends fitting over the ends of the con-

necting member and closed ends secured directly to the frame member with a spot-weld.

OTTO RUDD.
